UNITED STATES PATENT OFFICE.

JOHN W. NEISTRATH, OF BILOXI, MISSISSIPPI.

BROOM-HOLDER.

1,280,072.

Specification of Letters Patent. Patented Sept. 24, 1918.

Application filed May 23, 1916. Serial No. 99,435.

To all whom it may concern:

Be it known that I, JOHN W. NEISTRATH, a citizen of the United States, residing at Biloxi, in the county of Harrison and State 5 of Mississippi, have invented certain new and useful Improvements in Broom-Holders, of which the following is a specification.

This invention relates to broom or mop holders and its primary object is to provide 10 a household device that may be placed in position for holding a broom or mop in suspended position, thereby eliminating the possibility of the broom or mop becoming warped or distorted as implements of this 15 character often do when they are allowed to stand in a corner or some such similar place.

As a further object of the invention the device contemplates the provision of a broom 20 suspending device which can be mounted upon a stand, the stand being adapted to consume a minimum of space and adapted to be moved from one place to the other whereby the broom or mop may be placed 25 within convenient reach of the user.

The invention also aims to provide a broom or mop holder which is extremely simple in operation, the use of springs or 30 clips being eliminated and the weight of the implement being depended upon to hold the handle of the implement in suspended position.

A further object of this invention is the provision of a broom or mop holder which 35 consists of comparatively few parts and is simple in construction, but durable and well adapted to withstand the rough usage to which devices of this character are ordinarily subjected.

For a full description of the invention 40 and the advantages and merits thereof, reference is to be had to the following description and the accompanying drawings, wherein is illustrated the preferred form of my 45 invention, in which:

Figure 1 is a side elevation of the broom or mop holder, a pair of brooms being shown in dotted lines.

Fig. 2 is a top plan view.

Fig. 3 is a side elevation showing the 50 broom holder mounted upon a stand.

As illustrated by Figs. 1 and 2 of the

drawing the device consists of a fastening plate 1 which is substantially semi-ovoid in outline and is provided with screw holes 55 through which fastening screws or bolts 2 may be extended for fastening the plate 1 to the wall. Vertically extending, centrally located integrally formed with the plate 1 is the tongue 3 which, at each of its opposite sides, is provided with a vertically extending groove 4 in which the handle of the broom or mop lies when it is suspended from the holder. Pivotaly mounted at each end of the plate, is a fastening pawl 5, the free 60 ends of which are sharpened or provided with teeth 6 for engaging the handle of the broom or mop. When applying a broom or mop to the device it is only necessary to lay the end of the handle of the implement in 70 the groove and slide it upwardly, thereby throwing one of the pawls 5 upwardly on its pivot, and, when the broom or mop is raised to the desired height, by simply re-leasing the broom, it will be engaged by the 75 end of the pawl 5 and its weight will tend to draw the pawl downwardly thereby causing it to tightly grip the handle at its free end.

In Fig. 3 of the drawing is shown the device, as above described, mounted upon a standard 7 the lower end of which is provided with a tripod 8 for obviating the possibility of upsetting when the implement is suspended from the holder.

In reduction to practice I have found that the form of my invention illustrated in the drawings and referred to in the above description, as the preferred embodiment, is the most efficient and practicable, yet realizing that the conditions concurrent with the adoption of my device will necessarily vary, I desire to emphasize the fact that various minor changes in the details of construction, proportion and arrangement of parts may be 90 resorted to, when required, without sacrificing any of the advantages of my invention as defined in the appended claim.

I claim:

The combination of a support having a 100 vertical tongue arranged thereon in the center thereof and provided with opposite vertically extending grooves of a width less than the thickness of the said tongue, a

pair of broom handles, each adapted for reception in one of the said grooves, the depth of the latter being less than the diameter of the broom handle whereby a portion 5 of the latter will be exposed beyond the grooves and pivoted pawls mounted on the support and having their terminals adapted to swing into engagement with the broom

handles to normally maintain them in the said grooves.

10

In testimony whereof I affix my signature in presence of two witnesses.

JOHN W. NEISTRATH.
